COMBINED ASH TRAY AND MENU HOLDER

John C. Kuhlman, Cincinnati, Ohio

Application October 19, 1953, Serial No. 37,226

Term of patent 7 years

(Cl. D85—2)

To all whom it may concern:

Be it known, that I, John C. Kuhlman, have invented a new, original, and ornamental Design for a Combined Ash Tray and Menu Holder, of which the following is a specification, reference being had to the accompanying drawing, forming a part hereof.

The single figure is a front perspective view of a combined ash tray and menu holder, showing my new design.

The rear perspective view not shown has substantially the same appearance as the front perspective view shown in the single figure.

I claim:

The ornamental design for a combined ash tray and menu holder, substantially as shown and described.

JOHN C. KUHLMAN.
